GLENN H. BOWLUS, OF ALHAMBRA, CALIFORNIA

OIL WELL SURVEYING DEVICE

Application filed September 30, 1930. Serial No. 485,588.

My invention pertains to the art of drilling deep wells, and specifically to the determination of the deviation of such wells from the vertical.

5 The object of my invention is to provide a means for determining such deviation which shall be free from the numerous errors inherent in the commonly used "acid bottle" method.

10 My improved device consists substantially of a metallic ball resting on a spherical segment which forms the bottom of a retaining cup, this cup being sealed against the entrance of liquid and adapted in outer form to be lowered into or pumped down the drill pipe. The cup is so formed that when the device is set in a vertical position the ball will rest at the exact center of the bottom and will move away from this center as the device is 15 tilted, the extent of this movement being a measure of the deviation.

In order to make this measurement permanent while the device is being withdrawn from the hole the cup is partially filled with 20 some material which will remain liquid during the time required to run the device to the bottom of the drill pipe and will thereafter solidify.

In the accompanying drawing, Fig. 1 is a 25 longitudinal elevation of the device, partly in section. Fig. 2 is a cross-section of the longitudinally unsectioned device, taken on a plane through the ball 16 of Fig. 1.

Referring to the drawing, Fig. 1, which 30 illustrates in vertical section a preferred embodiment of my invention, 10 is a metallic body having such outer diameter as to slip easily into the drill pipe, 11 is a guide pipe or rod screwed into the lower end of the body and 12 a flange or spider having the same outer measurement as the body, the guide and flange being adapted to hold the device in axial alignment with the drill pipe. A plug 35 13 may be inserted into a tapped hole in the insertion of a rod to lift the disc from its position in the bottom of the cup after withdrawing the instrument.

The body is formed with a square shoulder 40 14 on which rests the disc 15 on which rests the ball 16. The upper face of this disc is

formed to a truly spherical curvature on a center which is exactly aligned with the axis of the device. The radius of curvature may be such that a deviation of say 6° from vertical will cause the ball to roll substantially 55 to the edge of the curved surface, though any other curvature may be used if preferred, the accuracy of the reading diminishing as the scope of the reading is increased.

The disc 15 may be of glass, polished on 60 both faces and etched on its upper surface with concentric circles each of which indicates 1° or a fraction of a degree of inclination. On such a disc the position of the ball 65 may be observed from below and may thus be read without making measurements. Or the disc may be of polished metal or quartz in which case the position of the ball must be measured by instruments applied from above.

The disc is held on the shoulder by a soft 70 gasket ring 17 retained by a compression ring 18 and the upper end of the cup is closed by a screw plug 19. The edges of the disc engage the approximate middle of the inner 75 edge of the gasket ring 17, which may be made of rubber. When screw plug 19 is tightened, compression ring 18 expands the gasket ring 17 by pressing upon it and forces its inner edge into tight contact with the disc.

It is important that all the joints be non-leaking under high pressure, as the intrusion of water or mud will prevent the functioning 80 of the device.

Before inserting the instrument into the drill pipe a suitable fluid is introduced on 85 top of the disc, in quantity sufficient to form a layer over the entire curved surface. The nature of this fluid must be such that it will maintain its fluid condition while the device is being passed to the bottom of the drill pipe, 90 so as to permit the ball to roll to the low point of the curvature after the instrument has come to rest, and such that it will solidify a short time thereafter, as say within ten minutes after being poured in. When the well 95 is known to be cold, that is if the temperature at the bottom is not over 100° F., a readily fusible material such as paraffin may be used, the device being heated to say 210° just prior to insertion and the residual heat maintaining 100

the paraffin in fusion for several minutes. Low melting point metallic alloys may also be used, but must be so selected as not to further alloy with the surface of the disc. For 5 higher temperatures materials which set slowly, such as dental cements, may be used. Any setting material must be ground to a state of impalpable fineness and mixed to a completely fluid condition in order not to 10 interfere with the free movement of the ball over the curved surface.

This device is used by inserting it into the drill pipe just prior to coming out and pumping mud fluid behind it until a rise in pressure 15 indicates that it has been stopped by the bit, after which it is allowed to stand for a few minutes to ensure the solidification of the fluid. The drill string is then run out in the usual manner, the instrument removed from 20 the last joint, the cap removed and the position of the ball on the disc measured.

It will be understood that while I have shown an illustrative embodiment of my invention in some detail I do not restrict myself 25 to the structure shown, the scope of my invention being limited solely by the following claim.

I claim as my invention:

In an instrument for measuring the inclination of a drill pipe: a transparent disc having a spherically curved upper surface and concentric rings marked on said surface, a ball of a high specific gravity solid resting thereon, and a shallow coating of a solidifiable material on that surface of said disc which carries the said ball.

In witness that I claim the foregoing I have hereunto subscribed my name this 25th day of Sept., 1930.
